(57)

CLAIM

The ornamental design for a pet leash, as shown and described.

DESCRIPTION

FIG. 1 is a perspective view of a pet leash showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan.

(Continued)

The broken lines depict portion of the pet leash that form no part of the claimed design.

1 Claim, 7 Drawing Sheets
